HOLDER FOR DARNING SOCKS

Eda Santarelli and Joseph E. Santarelli,
Kirksville, Mo.

Application February 8, 1949, Serial No. 75,198

1 Claim. (Cl. 112—121)

1

This invention relates to a device for holding articles of clothing while darning or sewing, and more particularly to a device for holding socks while darning them on a sewing machine.

It is an object of this invention to provide a device of the kind to be more particularly described hereinafter for holding socks or other tubular articles of fabric while darning them or sewing the article on a sewing machine. The sock holding device is provided with means for holding the sock securely in a flat, spread-out condition so that the sock may be fed to the machine with a constant speed and in the selected position relative to the darning foot or attachment of the machine. Arms are provided on the device for holding the article free from the needle of the machine while the article is being sewn.

Another object of this invention is to provide a device of this kind having a hoop or ring engageable in a sock or other tubular article of fabric having means for holding that portion of the article not in the hoop outwardly from the hoop to provide sufficient space and freedom for performing the necessary sewing operations to the portion of the article within the hoop.

Yet another object of this invention is to provide a device of this kind which is efficient in operation and simple in structure and formation for use and manufacture.

With the above and other objects in view, our invention consists in the arrangement, combination and details of construction disclosed in the drawings and specification, and then more particularly pointed out in the appended claim.

In the drawings:

Figure 1 is a top plan view of a sock holding device, constructed according to an embodiment of our invention.

Figure 2 is a side elevation thereof.

Figure 3 is a transverse section taken on the line 3—3 of Figure 1.

Figure 4 is a top plan view, partly broken away and partly in section, of a modified form of this invention.

Figure 5 is a fragmentary section, taken on the line 5—5 of Figure 4.

Figure 6 is a fragmentary side elevation, partly broken away and partly in section, of the inner ring of the sock holding device shown in Figure 4.

Referring to the drawings, the numeral 10 designates generally a holding device for holding socks or the like while darning them on a sewing machine. The sock holding device 10 is formed of an inner ring 11 and an outer ring 12 friction-

2

ally engaged thereon. The sock is adapted to be clamped between the inner and outer rings or hoops so that that portion of the sock disposed within the limits of the periphery of the inner ring may be supported in a flat extended position so that the darning or mending may be accomplished thereon in the desired manner. The sock holding device 10 is particularly constructed and arranged for use in mending the sock or other tubular fabric article on a sewing machine, and is formed for moving the sock in engagement with the sewing machine needle in the desired direction to conform to the operation to be performed on the article.

15 The inner ring 11 is formed of a flat vertically extending wall 14 formed into a horizontal loop. A bead 15 is formed on the upper marginal edge of the wall 14 and extends outwardly therefrom. A similar bead 16 is formed on the bottom edge 20 of the wall 14 extending outwardly therefrom and opening upwardly to confront the downwardly opening bead 15. The hoop 11 is substantially rigid for disposition within the tubular article for rigidly supporting the article during the sewing operation. The wall 14 together with the beads 15 and 16 may be formed of light sheet metal or other suitable material.

The outer ring 12 is formed in substantially the same manner as the inner ring 14 and includes 30 a vertically extending inner wall 17 having an outwardly rolled bead 18 and 19 on the upper and lower marginal edges thereof. The inside diameter of the outer ring 12 is slightly greater than the outside diameter of the inner ring 11, which outside diameter is measured about the outside edges of the beads 15 and 16. The outer ring 12 is adapted to loosely slide over the inside ring 11 for clamping the article of fabric therebetween.

40 An intermediate ring 20 is carried by the inside ring 11 on the outer side thereof. The intermediate ring 20 is formed of cork or other suitable compressible resilient material, and the upper and lower marginal edges of the intermediate ring 20 are adapted to be clampingly engaged 45 within the upper and lower beads 15 and 16 respectively. That portion of the intermediate ring 20 between the confronting edges of the upper and lower beads 15 and 16, is adapted to normally extend outwardly beyond the outside edge of the beads 15 and 16 to be engaged with the inside wall of the outer ring 12. The outside diameter of the intermediate ring 20, when mounted in the inner ring 11, is slightly greater 50 than the inside diameter of the outer ring 12.

and is adapted to be compressed for disposition within the outer ring 12 when the outer ring is engaged thereabout. By providing a resilient, compressible ring of this kind, between the inner and outer rings, a positive frictional grip is maintained by the clamping members or inner and outer rings 11 and 12 with the tubular article clamped therebetween.

In order to support those portions of the tubular article being mended from being disposed within the confines of the periphery of the inside ring 11, while that portion of the sock within the limits of the inner ring 11 is being mended, there is provided upwardly and outwardly extending supporting arms 21 about the marginal edge of the inside ring 11. The arms 21 are formed of metal rods, or other suitable material and extended downwardly through openings 22 in the outer surface of the upper beads 15. The lower end of the rods 21 is adapted to be engaged within the lower bead 16, for holding the rods 21 against pivoted or swinging movement relative to the inside ring. The rod 21 extends upwardly beyond the upper edge of the upper bead 15 a suitable distance, and the extreme upper end of the rod 21 is bent outwardly as indicated by the numeral 24. A ball 25, or other suitable rounded object is formed on the free end of the rods 21 in order to prevent any sharp corners from coming into engagement with the sock or other tubular article being supported thereon.

A plurality of rods 21 are secured in the inner ring 11 and disposed about the periphery thereof, being circumferentially spaced apart in such a manner that no portion of the sock, adjacent the portion of the sock clamped on the ring 11, will come into a position for obstructing the operation on that portion clamped between the inner and outer rings.

In Figures 4, 5 and 6 there is shown a modified form of this invention in which the inner and outer rings 11 and 12 are formed in substantially the same manner as noted above, and the intermediate compressible ring 20 is fixed on the inner ring 11 in exactly the same manner.

Arms 26, replacing the arms 21 noted in the form of the invention shown in Figures 1, 2 and 3, are carried by the inner ring 11. The arms 26 are formed of a short length of wire bent upon itself to the desired configuration, substantially the same as the external shape of the member 21. The arm 26 is formed of a length of wire looped upon itself substantially midway the length thereof to provide a pair of parallel arms 27 and 28 in engagement substantially along the length thereof. The arms 27 and 28 are connected together by a bight portion 29 which constitutes the upper outer end of the arm 26. The bight portion 29 of the member 26 is bent upwardly and outwardly from the upwardly extending arms 27 and 28, in substantially the same manner and direction as the arm 24 of the member 21. The lower ends of the arms 27 and 28 are engaged through an opening 30 in the top wall of the bead 15 substantially in the same manner as the arm 21 engages through the opening 22 noted above. As the arms 27 and 28 are extended through the

opening 30, the arms are bent in opposite directions about the periphery of the wall 14 along the upper edge thereof and are adapted to be disposed within the tubular bead 15. While the bead 15, in Figure 3, is noted as open on the lower edge thereof where the arm 21 extends downwardly, the lower edge of the bead 15a, noted in Figure 6, is closed or substantially closed for holding the outwardly extending arms 31 and 32 against downward sliding movement. The arms 27 and 28 are extended through the opening 30, and the arms 31 and 32 bent outwardly to their position as noted in Figure 6, prior to the completion of the forming of the bead 15a.

15 As noted in Figure 6, the upper and lower marginal edges of the intermediate ring 20 are clampingly engaged within the beads 15a and 16a which are formed in substantially the same manner as the beads 15 and 16, noted in Figure 3.

20 In the use and operation of the sock holding device 10, the inside ring 11 is initially engaged within the tubular member or sock so that the portion of the sock which must be mended is disposed within the marginal edges thereof.

25 That portion of the sock adjacent the portion to be mended is engaged about the members 21 or 26 so that the entire sock is held away from the sewing needle to permit the free movement of the needle within the ring and to permit the free

30 movement of the rings relative to the needle. When the inner ring 11 is disposed in the desired position in the sock, the outer ring 12 is positioned about the marginal edge of the inner ring 11 and will compress the intermediate ring 20, for clampingly securing the inner and outer rings together.

35 We do not mean to confine ourselves to the exact details of construction herein disclosed, but claim all variations falling within the purview 40 of the appended claim.

We claim:

A holder for darning a sock comprising a first hoop, a second hoop circumscribed about said first hoop and engageable with the portion of the sock trained over said first hoop, and a plurality of 45 upstanding supporting rods arranged in spaced relation about said first hoop and each having one end secured to said first hoop, the other end of each of said rods being inclined upwardly and terminating in a ball, said upstanding rods coacting 50 together to hold the portion of the sock above that clampingly held by said hoops out of obstructing position.

55 EDA SANTARELLI,
JOSEPH E. SANTARELLI.
